UNITED STATES PATENT OFFICE.

AUGUSTINE I. AMBLER, OF MILWAUKEE, WISCONSIN, ASSIGNOR TO HIMSELF, R. N. AMBLER, AND WARRICK MARTIN, OF SAME PLACE.

IMPROVEMENT IN NEEDLES.

Specification forming part of Letters Patent No. 37,996, dated March 24, 1863.

To all whom it may concern:

Be it known that I, AUGUSTINE I. AMBLER, of the city of Milwaukee, in the county of Milwaukee and State of Wisconsin, have invented a new and useful Improvement in Needles; and I do hereby declare that the following is a full, clear, and exact description of the same, reference being had to the accompanying drawings, forming part of this specification, in which—

Figures 1 and 2 are side views, on an enlarged scale, of sewing-machine needles with my improvement. Fig. 3 is a side view of a needle for hand-sewing, with the improvement.

Similar letters of reference indicate corresponding parts in the several figures.

In the several views of the drawings, *a* is the eye of the needle, made of the usual elongated form; and *b* is the slot made in one side of the eye. The outer edges of the slot are beveled on the outside to prevent their catching in the cloth or other material being sewed.

In constructing the needle with the slotted eye, more especially the machine-needle, it is preferable to make the eye a little nearer to that side in which the slot is formed or else to

make a slight fullness on the opposite side, as shown at *c* in Fig. 1, or to make the last-mentioned side straight to the point, so as to bring the point on one side of the center line or axis of the needle, as shown in Fig. 2, by either of which modes the weakening of the needle on one side by cutting the slot *b* is partly compensated for, and it is rendered stiffer than if the eye were in the center and the point in the center line or axis.

The slot *b* does not impair the efficiency of the needle, either for hand or machine sewing, experiment showing it to work as well as when the eye is unbroken on both sides.

Having thus described my invention, I claim and desire to secure by Letters Patent—

As an improved article of manufacture, a needle made with a lateral beveled opening into the eye and an increased thickness of metal on the side of the needle opposite the opening, all as herein shown and described.

A. I. AMBLER.
